UNITED STATES PATENT OFFICE.

AUGUST B. SCHOENKY, OF SOMERVILLE, MASSACHUSETTS, ASSIGNOR TO THE REECE SHOE MACHINERY COMPANY, OF BOSTON, MASSACHUSETTS, A CORPORATION OF MAINE.

SEWING-MACHINE.

1,209,340.

Specification of Letters Patent. Patented Dec. 19, 1916.

Application filed November 8, 1913. Serial No. 789,873.

To all whom it may concern:

Be it known that I, AUGUST R. SCHOENKY, a citizen of the United States, residing at Somerville, in the county of Middlesex and State of Massachusetts, have invented certain new and useful Improvements in Sewing-Machines, of which the following is a specification, reference being had therein to the accompanying drawing.

10 This invention relates to sewing machines, and is, for convenience, illustrated in connection with a sewing machine of the class used in the manufacture of shoes by the welt system, wherein the outsole and welt are 15 sewed together. That class of machine having been already known and illustrated in prior applications and patents, for example, in my prior application, Serial Number 789,624, filed September 13, 1913, it will be 20 unnecessary herein to fully describe all portions of the machine.

An object of the present invention is to generally improve and simplify the construction and operation of sewing machines 25 so as to give greater convenience and better efficiency.

Another object hereof is to afford a device operable at will, which may be employed by the operator after the machine has been 30 brought to a stop for effecting a release of the thread clamp, that is, in the present class of machine, the device which periodically locks the under thread during the formation of each stitch. Heretofore, it has 35 been customary in such machines to bring the same to a stop at that point in the cycle of operations where a stitch has been completed and set, and to thereupon by hand reverse the mechanism, for example, by a hand 40 wheel on the driving shaft, sufficiently to bring the parts to a position where the thread clamp is open, the thread clamp being naturally closed at the completion of the setting of the stitch; this reverse 45 movement of the shaft also leaves both the needle and the awl disengaged from the work so that the operator may thereupon remove the work from the machine unhindered either by the needle, the awl or the 50 closed condition of the thread clamp. By the present improvement this reverse movement is dispensed with and the thread clamp is opened by a means acting independently of the ordinary thread clamp operations.

55 Another object hereof is to afford a device

which, when operated at will, gives the combined results of unlocking the presser-foot from its position pressing upon the work and of opening the thread clamp, as above stated, and more particularly, to afford a 60 part, such as a treadle, which, when actuated, effects not merely an unlocking, if the presser-foot be locked, but also a lifting of the presser-foot from the work and, in addition, an opening of the thread clamp; so 65 that the operator, upon the stopping of the machine, has merely the single step to perform of depressing the treadle to enable him to draw the work and a portion of under thread from the machine.

70 Other objects hereof will be set forth in the hereinafter following description.

To the attainment of the several objects and advantages above referred to, the present invention consists in the novel combinations, arrangements, devices and parts set forth, described and illustrated in the following description and accompanying drawings.

75 First will be sufficiently described one 80 form of machine embodying the present improvements, and thereafter the novel features will be pointed out in the claims.

In the accompanying drawings forming a 85 part hereof, Figure 1 is a left-hand elevation, corresponding to Fig. 11 of said prior application, of the upper portion of a sole sewing machine embodying the present invention, the post 1 being supposed to extend to a base at the floor where the treadles 90 should be also located. Fig. 2 is a right-hand elevation of the machine shown in Fig. 1. Fig. 3 is a skeleton front view showing portions of the thread mechanism and the particular devices comprised in the 95 present invention. Fig. 4 shows in right-hand elevation certain parts detached from Fig. 2. Fig. 5 is a section on plane 5—5 of Fig. 4. Fig. 6 is a section on the plane 6—6 of Fig. 4. Fig. 7 is a right-hand elevation 100 similar to Fig. 2, but showing the parts in a different stage or position. Fig. 8 is an enlarged detail in right-hand elevation. Figs. 9 and 10 are similar views showing the parts in different stages of operation.

105

The same reference numerals designate corresponding parts in the several figures of the drawings.

Extending upwardly from any convenient base is the post 1 supporting at its upper 110

end the head or casting 2, affording support for various of the machine parts. The main shaft 3 extends from left to right in the upper part of the machine. Carried on the shaft 3 are cam disks for the different operations of the mechanism including the cam disk 7, shown in Figs. 2 and 7, and cam disk 8, shown in Fig. 1. A shuttle case 10 is indicated in the usual location, it being 15 for containing the shuttle which contains the bobbin, held in place and operated as usual.

Among the active instrumentalities in the machine are: work support 21 at the front, 15 presser-foot 23 above the work support, awl and fittings therefor beneath the work, needle 25 above the work, needle guide, thread loopers and hooks, and auxiliary or resilient take-up 30, main take-up 31, and the thread 20 clamp or arm 32. The various trains of mechanism and cam grooves for these instruments will not be described excepting so far as necessary to disclose the present improvement. The cam disk 7 at its right-hand side contains cam or groove 36 for automatically operating the presser-foot during each stitch, imposing an extra pressure upon it and releasing it, and a groove 135 which serves to intermittently open and 25 close the thread clamp 32 by swinging the arm thereof from and toward the opposing clamp member.

The feeding of the work may be effected by means of the awl which is shifted while 35 engaged in the work and returned after disengagement, there being a guide 44 in which feed slide 45 moves, carrying the awl post 46 in its to-and-fro movements, and a handle 54 serving for adjusting the 40 amount of feed for each stitch.

The presser-foot 23 is at the forward end of an arm swinging about a fixed stud and having one rear extension 68 rigid with the arm, and a second rear extension 69, 45 spring-connected therewith. Extending downwardly from arm 68 is link 71 connected at its lower end to arm 72, secured on a short longitudinal shaft 73, which 50 shaft has a pin at its upper side acted upon by spring 75, which pulls so as to normally keep the presser-foot with moderate pressure upon the work. This moderate pressure is in effect excepting when increased by the automatic mechanism or when the 55 presser foot is independently lifted. The presser-foot automatic operation may be effected through rack 76 on arm 69 engaged by dog 77, and similar rack 78 on arm 68 engaged by triple dog 79. Springs 80 and 81 press the dogs against the racks. The presser-foot operating lever 82, which 60 is pivoted at the rear, has a stud 83 engaging cam 36, and its forward end supports the dog 77 and spring 80. The arm 82 also 65 has heel 84, shaped to kick and thereby dis-

engage the triple dog 79 when the arm descends, at which time the dog 77 is also disengaged by a fixed pin 85. The operation of such mechanism is that when cam 36 forces arm 82 downward it serves, as described, to release the presser-foot from heavy pressure, this being effected automatically during each stitch at the proper time to permit the work to be fed forward by the awl between the work support and presser-foot, after which the arm 82, lifted by the cam, causes the reengagement of the dogs so as to put the presser-foot under heavy clamping pressure and lock it thus during the action of needle and awl. In this locking 80 action the dog 77 acts first through arm 69 to apply heavy spring pressure upon the presser-foot, and then the dog 79 acting through arm 68 positively locks the presser-foot in its depressed position. 85

To enable the presser-foot to be lifted at will, a treadle, not shown, may be employed, this being connected by a treadle rod 86 which may be depressed at will or, in some cases, automatically, upon the stoppage of 90 the machine. The rod 86 has at its upper end a head 87 with a lateral projection 88 adapted to contact with a stud 74 projecting leftward, as seen in Fig. 3, from the arm 72, so that pulling down the treadle rod lowers 95 the arm, thus raising the presser-foot. Such raising can not be effected without first releasing the dogs, and that may be effected by the following mechanism. Loose on shaft 73 is toothed plate 89, which extends forwardly and is connected to the upper end of the treadle rod, thus giving the latter support and guidance, and being swung by it. A second toothed plate 90, arranged loosely on the stud carrying the dog 79, has a 100 small number of teeth engaging the teeth on plate 89 in such manner that, when the treadle rod is depressed, the plate 89 first causes the plate 90 to rotate a short extent, whereupon the teeth become disengaged and the continued downward movement of the treadle rod merely elevates the presser-foot. The plate 90 is shaped and constructed to cause the disengagement of the dogs 77, 79, 105 when rotated clockwise, for example, by 110 laterally extending pins 93 and 91 on the dogs. The pins on the dogs, and the members 89 and 90 co-operating with them, and the operation of these parts, are illustrated and explained in my prior patent No. 1,171,466, granted February 15, 1916. Such 115 described mechanism may operate as follows: The projection 88 on the treadle rod head is spaced above the arm 72. The first part of its descent releases the dogs, and the projection then contacts with the arm 72. In this way the unclamping of the 120 heavy pressure is effected before the projection, acting upon the arm, causes the lifting 125 of the presser-foot. 130

The operation whereby the dogs 77 and 79 are unlocked by coöperation with the toothed plates 89 and 90 upon the depression of the pedal rod 86 may be explained 5 upon Figs. 8 to 10. Fig. 8, like Fig. 2, shows the normal running condition of the parts, the treadle rod 86 being elevated and the plate 90 being retracted leftward, the dogs being operative to impose the heavy 10 pressure intermittently upon the work during a part of each stitch. After the stoppage of the machine the depression of the pedal effects the following operations: First, the parts 89, 90 are shifted to the Fig. 9 15 position. The plate 90 has come into position where it is about ready to contact and actuate the pins 93 and 91 on the respective dogs. The further movement carries the parts to the Fig. 10 position, which is like Fig. 7. The plate 90 has acted upon the pins of the dogs and has removed both the dogs from their respective racks. Subsequent depression of the pedal has no further 20 effect on the plate 90, which, as will be clear 25 from Figs. 10 and 7, is locked against further movement.

A machine of the class referred to is supposed to have a stop mechanism, but as any type of stop mechanism might be employed, 30 the same, for convenience, is omitted herefrom, it being understood that the present improvements come into operation after the machine has been brought to a stop at the completion of the formation and setting of 35 a stitch. Patent No. 1,085,093, issued Jan. 20th, 1914 shows an available stop motion.

The under thread mechanism is seen in Fig. 1 in left-hand view, in Figs. 2 and 7 in right-hand view and in Fig. 3 in skeleton front view. The so-called auxiliary take-up 40 30 is in the nature of a thread cushion serving to pull and relax a portion of the under thread between the thread clamp and the take-up. This member 30 is preferably rendered resilient by a spring, and it moves 45 between stops. The under thread mechanism illustrated is particularly adaptable for lock stitch sewing machines, having stitching means serving for engaging upper and under threads with each other and with 50 the work. Reference has been made to the intermittently operating thread clamp 32 and the reciprocating take-up 31 between the clamp and the sewing point. In addition thereto, a tension device 118 may be 55 employed between the thread clamp and the supply of under thread, which may be drawn from a wax pot, also a reciprocating thread measure 119 between the clamp and the tension, and automatic mechanism for 60 harmoniously operating the clamp, the take-up and the measure in a previously known manner for the formation of each successive stitch. There may be a preliminary 65 tension 120 above the wax pot. The course

of the thread may be as follows: From the wax pot it passes to the preliminary tension 120, to the main tension 118, to the wheel of the thread measuring device or measure 119, between the members and 70 partly around one of the members of the thread clamp 32, to the wheel of the auxiliary take-up 30, to the wheel of the main take-up 31 and thence to the sewing point where are located the instruments for forming thread loops, pulling them through the work and interlocking them with loops of upper thread. The operation may be that, during each descending or take-up movement of the arm 31, the clamp 32 becomes 80 closed, so that the stitch is properly set in the work and, while the clamp is closed, the thread measure rises the proper amount to draw a new supply of thread from the tension devices. After the thread has been 85 so measured and before the succeeding take-up movement, the clamp 32 opens and the measured thread is drawn through the clamp before it again closes, previous to the setting of the next stitch.

The take-up 31 is fixed on transverse shaft 124, which extends through to the right-hand side of the machine, where at its extremity it is provided with a second arm 125 connected by a link 126 (see Fig. 3) with a 95 cam lever not shown, operated from one of the cams on the main shaft 3, so that the shaft's rotation causes the take-up to reciprocate.

The thread clamp 32 moves upwardly 100 against the co-acting clamp member for locking the thread and downwardly for releasing it. The arm 32 is secured upon oscillating sleeve 130, which, for convenience, surrounds the take-up shaft 124. The sleeve 105 at its right-hand end has a downwardly projecting arm 131 which is connected by an adjustable link 132 with the lower end of a cam lever 133, which, in turn, is provided with a stud 134 at its upper end engaging 110 cam groove 135 in the cam disk 7. By this arrangement the eccentric portions of the cam oscillate the lever and arms so as to open and close the clamp 32.

The thread measure 119 is at the right-hand end of a short shaft 138 having suitable bearings including bracket 139, and the shaft is oscillated through arm 140 projecting upwardly from it and having a stud 141 projecting into a groove 142 of an adjustable oscillating link 143. The link 143 at its lower end is pivoted to the outer end of arm 144. The forward and backward swinging movements of the link are effected by connecting rod 145 pivoted to the 125 link, and at its rear pivoted to the downwardly extending arm of a cam lever 147 whose other arm carries a stud engaging a cam groove 148 at the left face of a small cam disk 43 on the main shaft. The shaft's 130

rotation thereby oscillates the grooved link 143 to throw the stud 141 forwardly and backwardly for oscillating arm 140 and shaft 138 to swing the thread measure up and down. To adjust the amount of thread measured, the arm 144 may be swung to lift or drop the lower end of the link 143, thereby changing its pivot. In Fig. 1 the arm 144 is in highest position, its pivotal connection coinciding with the stud 141, and, consequently, there are no thread measure movements, but swinging arm 144 downward gives proportionately increasing thread measure movements, and this adjustment may, for convenience, be controlled from some member such as the presser-foot, whose position varies with the thickness of the work, so that the amount of thread allowed for each stitch depends on the work's thickness. The connections from arm 144 to the presser-foot may include the shaft 73, already mentioned, the arm 72, the link 71, etc., and there may be an adjusting device 154 between the arm and the link, as described and claimed in said prior application.

The operation of the machine may be further described as follows: The under thread on being drawn through the work is to be passed around the shuttle. As it passes the high point of the shuttle the auxiliary take-up will be at its highest point, the thread clamp at its low point or open, and the take-up at its high point, preferably the thread measure has moved completely up and is in the act of returning, the shuttle continuing its rotation, the take-up descends, causing the auxiliary take-up to be pulled to its low position and, at the same time, drawing the newly measured thread from the thread measure. After the thread measure has reached its lowest position, the thread clamp closes and the take-up continues its descent, slowing in speed toward the end of its motion until the stitch is completely set. When the machine is stopped, the parts are in this stage of operation, and the drawings so represent them. Thereafter, upon starting the machine, the take-up ascends a slight distance and remains stationary, the auxiliary take-up ascending nearly to its high position, imposing a tension on the thread. During this period the stitching mechanism operates to form a loop of under thread and place it upon the hook of the needle which rises through the work. During the same period, the clamp being closed, the thread measure moves upward for measuring further thread, after which it will descend as before described. When it reaches its high position, the thread clamp opens and thereafter the take-up resumes its ascent to high position. During the first part of this ascent of the take-up, the under thread is pulled through the work by the

needle and delivered from the needle to the shuttle, whereupon the shuttle starts rotating and reaches its high point practically simultaneously with the take-up reaching the high point of its motion. This completes 70 the cycle of operations for the formation of each stitch.

Having referred to the thread clamp, the stitching mechanism and the driving means for operating the thread clamp and stitching mechanism, reference will now be made to a device herein combined therewith operable at the will of the operator for opening the thread clamp. It will be understood that a stopping means is to be comprised with said driving means adapted to stop the machine with the thread clamp closed and also with the needle disengaged from the work, namely, at the point in the cycle when the stitch has been completed and properly set in the work. To open the thread clamp at will a lever or treadle device may be employed connected by the before mentioned treadle rod 86 with the mechanism for accomplishing the purpose stated. It is preferred to interpose in the connections between the driving shaft and the thread clamp the means for at will opening the clamp independently of the motion of the driving shaft. Thus, the link 132, pushing and pulling on the arm 131, normally acts through shaft 124 during each stitch to close and open the thread clamp. Herein there is shown interposed between the link and the arm a device enabling the arm to be swung independently of the driving shaft control, thereby permitting the opening of the clamp. For convenience, this connection, as shown, is a stud-and-slot connection. Commencing with the treadle rod 86, the train of mechanism 100 may be described as follows: The rod is provided with a lateral extension 160 carrying at its extremity a roller 161, which is adapted to contact with the upper side of and to depress an L-shaped extension 162 110 of the link 132. Thereby the depression of the treadle causes the link to swing downward.

The connection between the link and the arm 131 comprises a block 163, shown in detail in Figs. 4, 5, and 6, this block being connected by pivot 164 with the link 132, so that the block slides up and down within the slot shown at 165 in the arm whenever the treadle causes the link to move up and down. A spring 166 is shown tending to hold the block 163 in its upward or normal position and the lower end of the spring is accommodated in a barrel 167, permitting a longer and more efficient spring. In the 120 normal operation of the machine the spring sufficiently holds the block in its topmost position, and it would not depart from that position. When, however, the machine has been brought to rest in the position shown, 130

the treadle may be employed for causing the depression of the link 132 and the block 163. In causing this depression the link swings about a center located at the lower 5 end of the cam arm 133. It will be noted that the slot 165 is not concentric with the link's swinging movement and, therefore, the slot is in effect a cam coöperating with the block to cause a relative lateral movement when the link is swung. The lower 10 end of the slot 165 is farther from the link's center of swinging than is the upper end of the slot, and, therefore, the pulling down of the link will cause the arm 131 to swing 15 to the rear. In normal operation the link 132 is pulled to swing the arm 131 to the rear to open the thread clamp at each stitch. When the machine is not running and the treadle is depressed, the connections de- 20 scribed cause the arm similarly to swing to the rear, and thereby the thread clamp is opened at will. There has, therefore, been described a device operable at will for causing the opening of the thread clamp. It 25 will be noted that the depression of the treadle rod accomplishes more than the mere opening of the thread clamp. It effects the release of the presser-foot as well. Even though the thread clamp were open and 30 the work free from needle engagement, the work could not be drawn out of the machine properly if forcibly clamped under the presser-foot. This difficulty, however, is ob- 35 viated by the already described mechanism whereby the depression of the treadle rod, acting through the toothed plate devices shown in Fig. 8, causes the disengagement of the dogs 77 and 79 so as to relieve the presser-foot of its heavy compression. More- 40 over, the depression of the treadle rod does more than open the thread clamp and re- 45 lease the presser-foot, and, as shown herein, it also effects the actual lifting of the presser-foot to its elevated position. It will 50 be understood that in the normal action of the machine the presser-foot may vary in position owing to variations in work thickness, but it may be opened to a maximum extent more elevated than in normal 55 position, so as to disengage the work which the operator will have in hand at the time of depressing the treadle. This lifting of the presser-foot is effected by the hereinbelow described connections including the lug 60 88, seen in Figs. 2, 3 and 8, which is carried at the top of the treadle rod and serves, upon the descent of the latter, after the dogs are released, to press downwardly upon the arm 72, thus depressing the link 71 and 65 lifting the presser-foot in the manner previously described.

While the improvements above described are herein claimed broadly in connection with sewing machines, they have been par- 65 ticularly evolved and are especially useful

and important in connection with a two-thread lock-stitch sewing machine, which is illustrated herein, and to such a machine employing waxed thread such, for example, as, and more particularly, the sole sewing 70 machine of the type illustrated.

It will thus be seen that there has been described a two-thread, lock-stitch, wax-thread sole sewing machine embodying the principles of the present improvements and 75 attaining the objects and advantages there- of, and other advantages which will be ap- parent to those skilled in the art. Since many matters of detail, arrangement, com- bination, and other features may be modified 80 indefinitely without departing from the broad principles involved, no limitation to such features is intended excepting as set forth in the appended claims.

What is claimed is:

1. In a sewing machine adapted to be stopped with the stitch completed and thread clamp closed, the combination of a presser foot, stitching mechanism, operating mechanism, an automatic thread clamp com- 90 prising a movable thread clamping part shifted by connections from said operating mechanism during the formation of each stitch, said connections including a link en- gaging and actuating an arm, a contrivance 95 intermediate said link and arm permitting relative movement when said operating mechanism is idle, a movable device oper- able at will as a treadle adapted when shift- 100 ed to disengage the presser foot from the work, and connections between said device and said contrivance whereby the release of the thread is effected in the same operative shifting movement of said device by which the presser foot is disengaged. 105

2. In a sewing machine the combination of a presser-foot, stitching mechanism, a thread clamp opened and closed in forming each stitch, a take-up for taking up the thread of each stitch, means for applying 110 the presser-foot to the work, intermittent means for applying heavy pressure to the presser-foot during each stitch and for lock- 115 ing the presser-foot under such heavy pres- sure and releasing it during each stitch, mechanism for actuating such elements in 120 harmony, the same adapted to be stopped with the stitch completed, the thread clamp closed and the presser-foot locked under heavy pressure against the work, and a de- vice operable at will as a treadle having connections adapted in one operative move- 125 ment to effect the unlocking of the presser- foot and the opening of the thread clamp.

3. In a sewing machine the combination 125 of a presser-foot, stitching mechanism, a thread clamp opened and closed in forming each stitch, a take-up for taking up the thread of each stitch, means for applying 130 the presser-foot to the work, an intermittent

dog and rack device for applying heavy pressure to the presser-foot during each stitch and for locking the presser-foot under such heavy pressure and releasing it during each stitch, mechanism for actuating such elements in harmony, the same adapted to be stopped with the stitch completed, the thread clamp closed and the presser-foot locked, and a device operable at will as a treadle having connections adapted in one

operative movement to effect the unlocking of the presser-foot, the opening of the thread clamp, and the lifting of the presser-foot from the work.

In testimony whereof I affix my signature 15 in presence of two witnesses.

AUGUST R. SCHOENKY.
